**COMPARTMENTED CIGARETTE CASE
WITH EJECTORS**

Raymond Leclercq, Georges Leclercq, and Denise Leclercq, all of 184 Blvd. Zenobe Gramme, Herstal Iez-Liege, Belgium
Filed Mar. 18, 1965, Ser. No. 440,695
2 Claims. (Cl. 221—124)

The invention relates to a cigarette case with automatic cigarette feed.

There are already known various cigarette cases where the opening or the cigarette feed takes place automatically but they are complicated in construction and often too bulky to be slipped into the user's pocket.

A cigarette case in accordance with the invention has the advantage that it is of simple manufacture, with little bulk, and has the feature that it is constituted of a space for storing the cigarettes, the front part of which is provided with an arrangement for lifting up the cigarette facing a movable flap.

In accordance with a preferred embodiment of the invention, the cigarette case has a central support on one or both faces of which slides a cheek plate serving as a cover, by the removal of which it is possible to fill the case, the transverse front part of the same enclosing the lift arrangement, constituted of a pivoting lever, one end of which projects outside the case, and of a lift platform for the cigarette, the extension of which is in engagement with the other end of the said lever. With a case which is intended to contain cigarettes on the two faces of the central support, the lift arrangement is duplicated.

The invention will now be described with reference to the attached drawings, which are given by way of example and in no restrictive sense.

FIGURE 1 shows a front view in elevation of a case in accordance with the invention, arranged to contain twenty cigarettes.

FIGURES 2 and 3 show respectively a plan view and a side elevation of the case in accordance with FIGURE 1.

A cigarette case constructed in accordance with the invention, of rectangular shape and intended to contain twenty cigarettes, is constituted of a central support 1, on both of the faces of which there fits a cheek plate 2 forming a cover of U-shaped section, the ends of which are bent so that they can be inserted in suitable grooves 3 provided in the central support in order to make possible the sliding of the cheek plates or covers and accordingly the filling of the case.

At its rear part the central support is provided with a transverse surface 4 forming a lateral wall and at its front part has another transverse surface 5 on which is disposed the feed arrangement.

The cheek plates 2 have in front and on their horizontal upper part an opening 6 intended to make it possible for one cigarette to come out. The said opening is normally closed by a flap 7 which is under the action of a spring 8. The flaps with their springs are mounted on an axis 9 carried by a cover 10 of U-shaped section surrounding for the whole of its extent the transverse surface 5 of the support 1, the cheek plates 2 in closed position coming to rest against the said cover.

By means of pivots 11, there are mounted on the surface 5, levers 12, one part of which, 12', projects beyond the case to serve as a handling lever, whereas the other part 12'' which is fork-shaped is in engagement with the extension at a right angle 13' of a lift platform 13 disposed under the cigarette and facing the flap 7.

The pivoting levers 12 are under the influence of return springs 14 which are intended to move the handling le-

2

vers 12' upwardly and consequently the lift platforms downwardly.

The cigarettes contained in the case, on the two faces of the support 1 of the example shown in the drawing, tend to be pressed one after the other under the openings 6 by virtue of an elastic device, constituted in and on each face of the case, of two uprights 15, for example of plastic material, provided with leaf springs 16 disposed in scissor arrangement resting for one of the uprights on the adjacent upright, and for the other upright on the lateral rear wall 4 of the case, the front upright being further provided on its face opposite the leaf springs 16 with a leaf spring 17 adapted to rest against the last cigarette. The said return springs are riveted, welded or fixed in any suitable way to the uprights.

The elastic device is automatically compressed to make possible the refilling of the case when the cover is open, by virtue of buffers 18 with which the latter is provided. The said buffers serve also to restrict the course of the elastic device when the cover is closed and the last cigarette ready to be fed.

The use of such a cigarette case is extremely simple. For its refilling, one slides the cover 2 in the grooves 3, and, the elastic device 15, 16 yielding automatically thereby, one then arranges the cigarettes on the support 1, closes the cover 2 and the elastic device presses on the row of cigarettes to place the first of them on the lift platform 13 facing the flap 7. To obtain a cigarette all that has to be done is to actuate the handling lever 12' in a downward direction with the finger which is holding the case; the said lever engaging by its fork 12'' with the extension 13' of the lift platform 13 then lifts this, and consequently the cigarette which is resting thereon, lifting the flap 7.

In the above described way the cigarette comes up sufficiently out of its case to be presented, or in the case for example of the driver of a vehicle who cannot free two hands, it comes out enough to be put directly into the mouth.

It should be understood that a case in accordance with the invention can comprise only one single cover or cheek plate 2 and consequently contain only about ten cigarettes, the central support 1 being modified accordingly and the lifting arrangement being single and not duplicated.

By virtue of the very simple feed mechanism a case carried out in accordance with the invention even for twenty cigarettes has reduced bulk, and can be compared to an ordinary cigarette case which would contain the same number of cigarettes.

What we claim is:

1. A cigarette case comprising in combination, a central longitudinally extending frame, plates slidable on each side of said frame, said plates serving as covers and forming with said frame a pair of cigarette receiving compartments, means in the forward portion of said frame for lifting cigarettes, said means comprising a pair of pivoted levers disposed one above the other, the extreme portions of said levers extending outward of said case, a pair of lifting plates, one in each of said compartments, said lifting plates being coupled directly to the other ends of said respective levers, and delivery opening means through which the cigarettes are lifted.

2. A cigarette case comprising in combination, a central longitudinally extending frame, plates slidable on each side of said frame, said plates serving as covers and forming with said frame a pair of cigarette receiving compartments, means in the forward portion of said frame for lifting cigarettes, said means comprising a pair of pivoted levers disposed one above the other, the

extreme portions of said levers extending outward of said case, a pair of lifting plates one in each of said compartments, said lifting plates being coupled directly to the other ends of said respective levers, and delivery opening means through which the cigarettes are lifted and resilient follower means in each compartment comprising thin leaf springs in scissors-like arrangement.
